(57) **CLAIM**

The ornamental design for a printer as shown and described.

DESCRIPTION

FIG. 1 is a front view of a printer showing our new design; FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a perspective view thereof;

FIG. 8 is a front view of the printer of which a scanner cover is closed;

FIG. 9 is a top plan view of the printer of which a scanner cover is closed; and,

FIG. 10 is an enlarged cross-sectional view of the printer taken along line 10-10 in FIG. 9.

The dash-dash broken lines represent portions of the printer that form no part of the claimed design. The dash-dotted broken lines define the bounds of the claimed design but form no part thereof.

1 Claim, 10 Drawing Sheets
